UNITED STATES PATENT OFFICE.

ALEXANDER H. GENEST, OF CHESHIRE, CONNECTICUT.

AUTOMATIC GARAGE-DOOR OPERATOR.

Application filed April 25, 1922. Serial No. 556,475.

To all whom it may concern:

Be it known that I, ALEXANDER H. GENEST, a citizen of the United States, and a resident of Cheshire, county of New Haven, and State of Connecticut, have invented certain new and useful Improvements in Automatic Garage-Door Operators, of which the following is a specification.

This invention relates to door or gate operators and more particularly to means whereby the door or doors of a garage will be automatically opened and shut.

One object of the invention is to provide a device of this nature in which the door or doors of a garage will be opened when the weight of a motor car is thrown on a controlling element as the car approaches the door-way from either direction.

A further object is to provide a device of this nature in which the door or doors will be closed automatically upon the release of the controlling element when the car has passed completely thereover.

With these and other objects in view, there has been illustrated in the accompanying drawing one form in which the invention may be conveniently embodied in practice.

Fig. 1 is a perspective view showing the invention applied to the frame-work and approach of a garage.

Fig. 2 is a front view of the structure shown in Fig. 1, the base being shown in section.

Fig. 3 is a sectional side view of the approach showing one of the pivoted tracks in its normal position with the adjacent door locked.

Fig. 4 is a view similar to Fig. 3 but showing the pivoted track in depressed position and the adjacent door unlocked and in open position.

Referring now to the drawings in which like reference numerals denote corresponding parts throughout the several views, the numeral 10 represents a floor of suitable construction forming part of a garage, the latter also comprising corner posts 11 connected at their tops by bars 12, forming a rectangular frame. A doorway is formed at the front of the garage by door posts 13, extending from the floor to the front bar 12, and a bar 14 connecting the posts 13 below the front bar 12.

To close the doorway, provision is made

of two doors 15, 15, mounted on the corresponding door posts 13, 13, by hinges 16, so as to open outwardly. Each of these doors is urged outwardly by a helical torsion spring 17, the latter being secured at one end to the door 15 and at the other end to the adjoining post 13. To lock each of the doors 15 in closed position, provision is made of a bolt 18 slidably mounted in the floor and urged upwardly by a spring 19 to enter a recess or socket 20 in the lower edge of the door.

At the top of the doorway, each door is locked by a bolt 21 slidably mounted in the bar 14 and urged downwardly by a spring 22 to enter a socket 23 in the upper edge of the door.

The floor 10 is extended beyond the front of the garage to form an approach 24. The floor 10 is also provided with a pair of parallel grooves or recesses 25, 25, to receive movable tracks 26 supported at their outer ends on pivots 27. These tracks normally are preferably substantially flush with the upper surface of the floor 10. Projecting downwardly from each of the tracks 26 is a vertical reinforcing strip or rib 28 which gradually decreases in depth away from the pivoted end of the track.

When in depressed position, each track is supported by its rib 28 which rests on the bottom of the corresponding recess 25. The dimensions of the apparatus may be varied in accordance with the size of car, and other conditions. For example, in one installation, the tracks 26 are about eleven feet long, and when a motor car was resting upon them, the tracks were depressed about two inches.

As clearly shown in Fig. 1, the tracks 26 extend a substantial distance within the garage so that they may be depressed by the car as the latter approaches the doors from the inside.

To enable the car to pass smoothly from the tracks to the floor and vice versa, at the inside of the garage, a pair of inclined portions 28^a are formed in the floor adjacent the inner ends of the recesses 25.

The tracks 26 are normally supported by a cross bar 29 of suitable material, such as iron. The cross bar 29 passes through slots 105 in the ribs 28, and is connected by pins 30 with the bolts 18. At its ends, the bar 29 is connected with vertical rods 31 pivoted at

their upper ends to the outer ends of levers 32 pivoted on brackets 33 on the bar 14. It will be evident that, upon depression of the tracks 10 by a car, the bolts 18 and 21 will be withdrawn to ineffective positions.

Provision is also made for holding the tracks 26 in raised position and for closing the doors 15 when the car runs off either end of the tracks. To this end, a lever 34 at 10 each side of the doorway is mounted on a pivot 35 supported at one end by a bracket 36 on the corner post 11, and at the other end on a bracket 36 carried by the door post 13. The short front arm of the lever 34 is pivotally connected with the rod 31, previously described, and the long rear arm is inclined downwardly at a considerable angle. A rope or other flexible member 37 is attached to the rear end of the lever and passes 15 through and is connected with an eye 38 secured to a counterbalance or weight 39. The rope 37 then passes upwardly to, and over a pulley 40 secured to the bar 12 at that side of the frame. The rope 37 is then brought 20 forward and across the garage and secured to an eye or staple 41 on the inner face of the door 15 on the other side of the garage.

In operation, when the tracks are depressed by a car, the rods 31 are drawn downwardly and swing the levers 34 about their pivots against the action of the weights 39. It will be observed that, due to the difference in length of the arms of each of the levers 34, the slight downward movement of the forward end of the lever will cause a considerable upward movement of the rear end thereof. The downward movement of the rods 31 having been accompanied by the withdrawal of the bolts 18 and 21, the doors 25 15 will now be swung to their open or dotted-line positions, as shown in Fig. 1.

Upon release of the tracks 10 from the weight of the car, the tracks and the bolts 18 and 21 will be restored to their normal 30 positions, and the weights 39 will close the doors to which they are connected, the doors 15 then being locked in closed position by the bolts 18 and 21. In order to insure the return of the doors 15 to closed position 35 without being blocked by the bolts 18 and 21, lost motion may be provided between the bolts and the actuating means therefor by forming slots on said bolts which fit loosely over the lever pivots. Moreover, the heads 40 of the bolts may be beveled, and the adjacent edges of the doors may be so shaped that, if necessary, the bolts may be pressed back by the doors in moving to closed position, and

then permitted to snap into the corresponding sockets.

Any desired additional means may be provided to lock the doors shut after the car has gone into the garage or has left on a trip. Ordinarily, however, such additional locking means will be unnecessary as the bolts 45 18 and 21 will securely hold the doors in closed position.

While there has been disclosed in this specification one form in which the invention may be embodied, it is to be understood that 50 this form is shown for the purpose of illustration only, and that the invention is not to be limited to the specific disclosure but may be modified and embodied in various other forms without departing from its spirit. In 55 short, the invention includes all the modifications and embodiments coming within the scope of the following claims.

Having thus fully described the invention, what is claimed as new, and for which it is 60 desired to secure Letters Patent, is:

1. In a garage-door operating mechanism, a door, means to urge the door to open position, means to releasably hold the door in closed position, vehicle-actuated mechanism 65 for releasing said holding means, a weight connected to said door for urging it to closed position, vehicle-operated means for raising said weight to permit said door to open, said weight-raising means being connected to said 70 releasing mechanism whereby said weight will not only serve to close said door when the vehicle has left its actuating position, but will also serve to restore said door-holding 75 means to holding position.

2. In a garage-door operating mechanism, a pair of doors, means to urge said doors to open position, means to releasably hold the doors in closed position, a pair of levers connected to said holding means, vehicle-actuated means connected to said levers to release said holding means, a pair of weights connected to said doors for urging them to closed position, a pair of levers rigidly connected to said vehicle-actuated means and loosely connected to said weights, said weights being adapted to be raised by said vehicle-actuated means to release said doors, and said vehicle-actuated means being adapted to be restored to original position by said 100 weights when the vehicle has left its actuating 105 position.

In testimony whereof, I have affixed my signature to this specification.

ALEXANDER H. GENEST.
